Primary Examiner — Shannon W Morgan*Assistant Examiner* — Kristin E Reed(74) *Attorney, Agent, or Firm* — Seed IP Law Group LLP; Jared M. Barrett(57) **CLAIM**

The ornamental design for a component for suspending ceiling panels, as shown and described.

DESCRIPTION

FIG. 1 is a front perspective view of a component for suspending ceiling panels showing my new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a left side elevational view thereof; and,

FIG. 7 is a right side elevational view thereof.
